VENTILATING DEVICE

Emile St. Aubin, Kankakee, Ill.

Application January 10, 1938, Serial No. 184,257

4 Claims. (Cl. 4-213)

This invention relates to a ventilating device and more particularly to a device of this character adapted to be installed in connection with the seat of a toilet bowl and extract air and obnoxious odors from the bowl during use of the bowl.

One object of the invention is to provide a device of this character which can be very easily installed in connection with a toilet bowl and a suction pipe forming part of the apparatus secured under the seat where it will be out of the way and at the same time in such a position that a good suction will be created entirely about the upper portion of the bowl.

15 It is another object of the invention to provide improved means for mounting the suction pipe and so associate an elastic mounting ring for the pipe with the same that, when the seat of the bowl is in a lowered position, this elastic ring may be compressed by contact with the bowl and fit tightly about the suction pipe. It will thus be seen that a tight joint will be formed about the suction ring and in addition the suction pipe itself will be prevented from making contact with 25 the bowl and becoming bent out of its proper shape.

Another object of the invention is to so form the suction pipe that its diameter will increase towards its outlet and thus gradually increase the 30 capacity of the pipe and provide ample room therein for the carrying off of air withdrawn from the bowl.

Another object of the invention is improved means for mounting the air pipe for swinging movement to a raised or lowered position with the seat, this means including a rotatably mounted pipe leading to a suction fan having an electric motor associated therewith.

Another object of the invention is to provide a device of this character wherein the motor and the suction fan are mounted upon a bracket constituting a portion of a mounting by means of which the seat is mounted for swinging movement, the mounting means for the seat being so constructed that it may extend across the rear portion of the bowl and dispose the suction fan and motor at either side of the bowl desired.

The invention is illustrated in the accompanying drawings, wherein

50 Figure 1 is a perspective view of a toilet bowl equipped with the improved ventilating means.

Figure 2 is a sectional view taken through the bowl and ventilating means along the line 2-2 of Figure 1 but showing the seat and its cover in 55 a lowered position,

Figure 3 is a view taken along the line 3-3 of Figure 2.

Figure 4 is a sectional view upon an enlarged scale taken transversely through the seat and the suction pipe and mounting ring carried thereby with a portion of the bowl being also shown in section, and

Figure 5 is a fragmentary sectional view taken along the line 5-5 of Figure 1.

The bowl 1 is of a conventional construction 10 and it is formed with the usual water channel 2 from which water is discharged through the openings 3, water being fed to the channel 2 through a pipe 4 from the usual flush tank 5. Over the bowl is disposed a seat 6. There has also been 15 shown a cover 7, but it is to be understood that the cover may be omitted if so desired.

In order that a suction may be created in the bowl and air and obnoxious odors withdrawn during use of the bowl, there has been provided a 20 suction tube or ring 8 which substantially conforms to the outline of the seat and is disposed against the under face thereof in encircling relation to the opening of the seat, but attention is called to the fact that this ring is spaced from 25 marginal edges of the seat, as clearly shown in Figure 1. Referring to this figure, it will also be seen that the diameter of the tube gradually increases from the front of the seat towards the rear of the seat and, therefore, the capacity of 30 the tube gradually increases towards the rear end of the seat where the tube is integrally connected with a hollow arm 9 constituting a side extension of a suction pipe 10. A plurality of 35 openings or perforations 11 are formed in the tube 8 in spaced relation to each other in order that air may be drawn into the tube from the bowl. While the openings 11 have been shown circular, it is to be understood that they may be of any 40 desired outline in cross section, such as square or oblong. The suction pipe extends transversely of the bowl and seat rearwardly thereof and serves not only as a suction pipe but also as means for pivotally mounting the seat. Referring to Figures 45 2 and 4, it will be seen that the tube 8 is encircled by a retainer strip 12 formed of rubber or other elastic material. This strip 12 fits snugly about the tube and is mounted in a ring or frame 13 formed of sheet metal and secured against the under face of the seat 6 by a suitable number of 50 screws 14. Portions of the flange 15 of the frame are bent inwardly, as shown at 16, in order to have gripping engagement with the ring or pad 12 and hold the pad in place. From an inspection of Figure 4, it will be seen that the pad 55

projects beyond the flange 15 a sufficient distance to prevent contact of this flange with the bowl when the seat is lowered. Therefore, when the seat is lowered and subjected to pressure, the pad 5 will be expanded laterally and have tight binding engagement with the tube. This will cause the tube to be very firmly secured and in addition will form a tight joint about the tube and leakage of air about the tube prevented.

10 A suction fan 17 has its inlet neck 18 engaged about one of the reduced end portions 19 of the exhaust pipe 10. The exhaust fan is provided with a base 20 which rests upon a bracket 21, one end portion of which is bent upwardly, as shown 15 at 22, and supports an electric motor 23, the source of which is coupled to the shaft 24 of the fan 17. While it has been stated that the shaft of the motor is coupled to the shaft of the fan, it will be obvious that the motor may have a shaft of sufficient length to extend into the housing of the 20 fan and have the hub of the fan blade mounted thereon. The bracket 21 constitutes a portion of a plate 25 which extends across the rear portion of the bowl and carries bearing sleeves 26 through 25 which the shaft 10 is journaled. These sleeves 26 are detachably secured by screws 26' or in any other desired manner, and since they fit about the reduced end portion 19 of the exhaust pipe 10, the pipe will be prevented from shifting longitudinally through the bearings and the seat will be prevented from shifting out of its proper position over the bowl. Hinge ears 27 extend from the exhaust pipe back of the seat, and to these ears are pivoted the rear ends of the hinge strap 30 35 28, by means of which the cover 1 is mounted for swinging movement to a raised or lowered position. It will thus be seen that the cover may be swung vertically independent of the seat or the seat and cover may be moved together. When no cover is provided, the hinge ears 27 may be omitted.

When this device is in use, it is applied to the bowl, as shown in Figure 1, and the fastener 29 carried by the tongue 30 tightened to firmly hold the mounting in place across the rear portion of the bowl. The frame 13 carrying the pad 12 and the exhaust tube 8 is secured against the under face of the seat, and in view of the fact that this frame is firmly secured by the screws 45 50 55 60 65 70 75 14, the suction tube or exhaust tube will be maintained in its proper relation to the seat. The discharge neck 31 of the fan extends rearwardly from the housing thereof into the wall 32 back of the bowl and is connected with a vent pipe 33 extending vertically through the wall. It will thus be seen that any air withdrawn from the bowl by the fan will be discharged through the pipe or nozzle 31 into the vent and pass upwardly through the vent. Instead of disposing the motor and fan at the left hand side of the bowl, they may be at the right hand side thereof, in which case the plug 34 closing one end of the exhaust pipe 10 will be removed and transferred to the other end thereof. This should only be done in cases where the vent pipe extends vertically in the wall in a position which would make it inconvenient to connect the pipe 31 with it when the motor and the fan are located at the left side of the bowl. The seat is disposed in its lowered position in which the under face of the pad 12 rests upon the water channel 2 and when the seat is occupied pressure will cause a tight joint to be formed between the seat and the bowl and also about the exhaust tube 8. A person occupying the seat will also apply pressure to a

switch 35 mounted in a side portion of the seat and connected with wires 36 leading from the motor. This will cause the motor to be set in motion and air will be drawn from the bowl through the perforations 11 into the tube 8 and through this tube into the exhaust pipe or tubular shaft 10 leading to the fan. The air entering the fan housing will be expelled through the pipe 31 and pass through this pipe to the vent. It will thus be seen that air and obnoxious odors will be withdrawn from the bowl and discharged into the vent pipe leading to the roof of a building and fouling of air in a room will be avoided.

Having thus described the invention, what is claimed as new is:

1. In combination with a toilet bowl, a mounting at the back of the bowl extending transversely thereof with one end portion projecting from a side of the bowl, bearings rising from said plate, an exhaust pipe rotatably supported through the 20 bearings of said mounting and extending transversely of the bowl, an exhaust fan carried by the extended end portion of said mounting and having its inlet connected with the adjacent end of the exhaust pipe, a discharge pipe for said fan 25 adapted to be connected with a vent pipe, a seat, a suction tube secured under said seat and extending about the same and opening into said exhaust pipe, and an electric motor for said fan mounted upon the extended end portion of said 30 mounting outwardly from the fan and having a control switch carried by said seat in position to be closed by the weight of a person occupying the seat.

2. In combination with a toilet bowl, a mounting at the back of the bowl, an exhaust pipe rotatably carried by said mounting and extending transversely of the bowl, a suction fan connected with one end of said exhaust pipe, a motor for said fan, a seat, a tube secured to the under 40 face of the seat about the opening in the seat, said tube being formed with perforations and increasing in diameter toward the rear end of the seat to provide gradually increasing capacity, said exhaust pipe having a hollow extension intermediate its length united to the enlarged rear portion of said tube and constituting a throat connecting the tube with the exhaust pipe, and means for setting the motor in operation when the seat is occupied.

3. In combination with a toilet bowl, an exhaust pipe extending transversely of the rear portion of the bowl and rotatably mounted, an exhaust fan connected with said exhaust pipe, a motor for said fan, an exhaust tube disposed 55 under the seat and extending about the same between inner and outer marginal edges of the seat, said tube being perforated to provide air inlets and having its rear portion communicating with the exhaust pipe, an annular frame secured 60 against the under face of said seat and surrounding said tube and having an outer peripheral wall formed with an inwardly extending lower flange, and a packing of elastic material mounted in said frame and fitting tightly about the exhaust tube between the tube and the flanged wall of the frame and projecting beyond the tube and the flange of the frame whereby the packing will be firmly held in place and the outer face of the packing may make contact with the bowl and the 70 packing be compressed and form a tight joint about the exhaust tube and between the seat and bowl when the seat is in a lowered position and subjected to the weight of a person occupying the same.

4. In combination with a toilet bowl having a flush channel about its top, an exhaust pipe extending across the rear portion of the bowl and rotatably mounted, a suction fan connected with one end of said exhaust pipe, a motor for said fan, a seat having an opening, a suction tube extending about the seat opening in spaced relation to inner and outer marginal edges of the seat, the rear portion of said tube having communication with the exhaust pipe, an annular plate secured to the under face of said seat about

said tube and along its outer marginal edge being formed with a depending flange projecting from the seat, and elastic packing in said frame fitting closely about the tube between the tube and said flange and projecting outwardly beyond the flange of the frame, portions of the flange being bent inwardly to provide a lip gripping the packing and holding the same in place about the tube. 5
